UNITED STATES PATENT OFFICE

127,693

DESIGN FOR A DOLL FACE MASK OR SIMILAR ARTICLE

Arthur A. Gerling, New York, N. Y., assignor to Knickerbocker Toy Co. Inc., New York, N. Y., a corporation of New York

Application January 25, 1941, Serial No. 98,385

Term of patent 7 years

To all whom it may concern:

Be it known that I, Arthur A. Gerling, a citizen of the United States, residing at New York city, in the county of New York and State of New York, have invented a new, original, and ornamental Design for a Doll Face Mask or Similar Article, of which the following is a specification, reference being had to the accompanying drawing, forming part thereof.

In the drawing

Fig. 1 is a front elevational view of a doll face mask, showing my new design; and

Fig. 2 is a side view thereof partly in perspective.

I claim:

The ornamental design for a doll face mask or similar article, substantially as shown.

ARTHUR A. GERLING.
